UNITED STATES PATENT OFFICE

DAVID B. HOOVER, OF ELIZABETHTOWN, PENNSYLVANIA

CONCRETE-MIXING MACHINE.

1,029,126.

Specification of Letters Patent. Patented June 11, 1912.

Application filed September 10, 1910. Serial No. 581,361.

To all whom it may concern:

Be it known that I, DAVID B. HOOVER, a citizen of the United States, and a resident of Elizabethtown, in the county of Lancaster and State of Pennsylvania, have invented certain new and useful Improvements in Concrete-Mixing Machines, whereof the following is a specification, reference being had to the accompanying drawings.

This invention particularly relates to concrete mixing machines of the class wherein the mixing of the constituent elements of the concrete product is effected by gravitation.

The principal objects of this invention are to provide a concrete mixing machine of the gravity type, with a plurality of mixing hoppers disposed in vertical alinement, and provided with means to collect a predetermined quantity of material in said hoppers, and to automatically effect the discharge intermittently of the material accumulated in each mixing hopper, into the subjacent hopper, and to provide means to vary the amount of accumulation of material sufficient to effect the discharge of said hoppers.

Further objects of this invention are to provide spraying pipes suitably disposed to introduce water at different predetermined stages of the mixing operation, and to provide valves operatively connected to control the flow of water in the respective spraying pipes in a predetermined sequence.

The form of this invention, hereinafter described, provides a concrete mixing machine, with a plurality of mixing hoppers forming conoidal frustums, disposed in vertical alinement between an inlet hopper and a discharge hopper; a manually actuated slide-gate arranged to control said inlet hopper; a manually actuated slide-gate arranged to control said discharge hopper; substantially bell-shaped spreaders overlying each of said mixing hoppers and said discharge hopper; a conical gate for each mixing hopper, comprising complementary semi-conical jaws separately pivoted to said hopper and arranged to be intermittently forced apart by the material in said hopper, when a predetermined quantity of said material is accumulated therein; weights carried by said jaws tending to close said gate, and adjustable with respect thereto, to vary the amount of material accumulated in said mixing hoppers necessary to effect the automatic opening of said gate; spraying pipes

respectively arranged to direct water into the receiving hopper, and mixing hoppers; and a casing inclosing said hoppers and having openings for the convenient access to the inclosed mechanism, closed by doors hinged to said casing.

This invention further includes all of the various novel features of construction and arrangement hereinafter more definitely specified.

In the accompanying drawings, Figure 1 is an elevational view, partly in section, of a convenient embodiment of this invention; Fig. 2 is a vertical longitudinal sectional view of the structure shown in Fig. 1, taken on the line 2—2 in said figure; Fig. 3 is an enlarged fragmentary sectional elevation showing one of the mixing hoppers, with its gate in open position; Fig. 4 is an inverted plan sectional view taken on the line 4—4 in Fig. 1; Fig. 5 is a plan sectional view taken on the line 5—5 in Fig. 1; Fig. 6 is an inverted plan sectional view taken on the line 6—6 in Fig. 1; Fig. 7 is a perspective view of the gate and its supporting link connections *per se*; Fig. 8 is a plan view of the valve arranged to control the flow of water to the hoppers; Fig. 9 is a side elevational view of said valve; Fig. 10 is a plan sectional view taken on the line 10—10 in Fig. 9; Fig. 11 is a central vertical sectional view taken on the line 11—11 in Fig. 8; and Fig. 12 is a diagrammatic view showing five positions of two of said valves coupled to control the flow of water to the respective hoppers in a predetermined sequence.

In said figures, the cylindrical casing 10 supports the receiving hopper 11 at the top thereof, and the discharge hopper 12 at the bottom, provided with the chute 13 terminating exterior to said casing, and the mixing hoppers 15 and 16 are disposed in vertical alinement, preferably at uniform distances, intermediate of said receiving and discharge hoppers.

The hopper 11 is substantially conical, and its walls taper downwardly to the restricted outlet 18, which is arranged to be closed by the slide-gate 19, mounted for reciprocation in the guides 20, and connected by the link 21 with the bell crank lever 22, which is pivoted at 23, and provided with the operating handle 24.

The discharge hopper 12, like the receiving hopper 11, is substantially conical, and its walls taper downwardly to the restricted

outlet 25, which is arranged to be controlled by the slide-gate 26, mounted to reciprocate in guides 27, and connected by the link 28, with the bell crank lever 29, which is pivoted at 30, and provided with the operating handle 31, for the convenient control of the distribution of the mixed product.

The mixing hoppers 15 and 16 are secured to the casing 10 by the rivets 32, and are substantially conoidal in form, and curvedly taper downwardly to the restricted outlet 33, which is controlled by the pivoted gate, comprising the complementary substantially semi-conical jaws 34 and 35. Said jaws 34 and 35 are pivoted to oscillate on the respective links 36 and 37 and are supported thereby; said links being pivoted for oscillation to the brackets 38, which are secured to the opposite sides of each of said mixing hoppers, as best shown in Figs. 2 and 6.

The gate jaws 34 and 35 are provided with arms 40 and 41, which respectively carry adjustable weights 42, secured in adjusted position by set screws 44, whereby the amount of material sufficient to effect the required pressure to open said jaws may be conveniently varied by setting said weights in the positions required.

It may be noted that the product of the weights, and the leverage due to their distance relative to the center of oscillation, must be commensurate with the quantity of material desired to be accumulated in the hopper before said material is automatically discharged. For instance, if it is desired to accumulate fifty pounds of material in the mixing hopper before its automatic discharge therefrom, the weights 42 are shifted to a position to maintain said gate jaws 34 and 35 together in closed position to prevent the escape of material from said hopper, until the desired fifty pounds are accumulated therein, when said material forces said jaws apart in opposition to said weights, and it is spilled out upon the subjacent spreader 45.

Each spreader 45 is substantially conical in form, having its slanting walls slightly concaved and approximating a bell configuration, and having its apex extending toward the superjacent hopper, in substantially concentric relation with its outlet. Each of said spreaders 45 is supported by the inverted V-shaped brackets 46 secured to the walls of the casing 10, in such position that its bottom edge extends into proximity to the top edge of the subjacent hopper; so that as the material to be mixed is dropped upon a spreader 45, it is thrown by the flaring walls of said spreader laterally, in all directions against the upper region of the walls of the subjacent hopper, and is collected therein until sufficient material is accumulated to effect the automatic opening of its controlling gate. A spreader 45 is superim-

posed upon each of the mixing hoppers, and said discharge hopper.

As best shown in Fig. 3, the gate jaws 34 and 35 are pivoted to swing apart on the pivots 48 and 49 at the upper ends of the respective links 36 and 37, and are pivoted to oscillate on pivots 50 and 51 at the lower ends of said links, so that, as may be observed, said jaws are capable of swinging apart while their upper peripheries remain in contact with, and slide upon, the exterior surface of the mixing hopper.

Water is supplied to the hoppers 11, 15 and 16 through the respective spraying pipes 53, 54 and 55, which have suitable perforations for directing jets of water into the material to be mixed, and which are connected by their respective branches 57, 58 and 59 with the water supply pipe 60, leading water from any suitable source of supply.

The supply pipe 60 is provided with valves 62 and 63, which are arranged to control the supply of water to the branches 57, 58 and 59, and their respective spraying pipes 53, 54 and 55, which are connected by the rod 61, to be contemporaneously actuated by the movement of the valve lever 64 to successively admit water into the respective spraying pipes 53, 54 and 55 in a predetermined sequence.

The valves 62 and 63 are similar in construction, and consequently the details of the former only are illustrated in Figs. 8 to 11, inclusive. As shown in said figures, the valve casing 65 is provided with an inlet 66 and an outlet 67, leading to the spraying pipe 53, and controlled by the gate 68, and the outlet 70 connected with the valve 63, as shown in Fig. 1, and controlled by the disk 71, carried by the gate 68, and having the aperture 72 arranged to register with the outlet 70, to admit water to the subjacent valve 63.

The casing 10 forms a cylindrical closure for the hoppers, and prevents the accidental spilling or splashing of the material as it gravitates from one hopper to the other in its descent through the machine. Said casing is conveniently provided with opposed doors 73, which are arranged to swing on the hinges 74 and which are respectively provided with the handles 75, said doors being provided to permit the convenient adjustment or cleaning of the mechanism inclosed by said casing.

Referring now to the coupled valves 62 and 63, diagrammatically illustrated in Fig. 12, the first position shows the valves set to open the gate 68 of the valve 62, and to close the disk 71, to admit water to the spraying pipe 53; the second position shows said valves set to close the gate 68, and to open the disk 71, of the valve 62, and to open the gate 76 and close the disk 77 of the valve 63,

to admit water to the spraying pipe 54; the third position shows the valves set to close the gate 68, and to open the disk 71 of the valve 62, and to close the gate 76 and to open the disk 77 of the valve 63, to admit water to the spraying pipe 55; the fourth position shows a condition similar to the third position; and the fifth position shows the gate 68 and the disk 71 in a position to close both 10 of the outlets 67 and 70, and thereby prevent water entering any of the spraying pipes 53, 54 and 55.

It may be observed from the foregoing description of the diagrammatic view shown 15 in Fig. 12, that the valves are so constructed and related that the admission of water to any one of the spraying pipes effects a termination of supply of water to the other spraying pipes.

20 The operation of the mixing device is effected as follows: Layers of cement 80, sand 81 and stone 82, shown in Fig. 2, are introduced into the receiving hopper 11, and when the desired amount is collected; the 25 operator shifts the slide valve 19 by the movement of the lever 22, and permits the unmixed material to escape through the outlet 18 and to fall upon the spreader 45, which is disposed beneath said receiving hopper.

30 The material thus dropped from the hopper 11, is thrown outwardly by the subjacent spreader 45 against the walls of the mixing hopper 15, and is collected therein: the 35 amount of material accumulated in said hopper being determined by the relation of the weights 42 to the gate jaws 34 and 35. When, however, the accumulated material reaches the desired weight to overcome said weights 42, the opposed jaws 34 and 35 are 40 spread apart by said material, and it is precipitated upon the subjacent spreader 45, superjacent to the mixing hopper 16, and is again thrown outwardly by said spreader against the walls of the mixing hopper 16.

45 The operation of the hopper 16 is the same as the superjacent hopper 15, so that when the accumulated material in the hopper 16 is sufficient to open its gate, said material is precipitated upon its subjacent spreader 45, 50 which is superimposed upon the discharge hopper 12, where it is collected and discharged as desired.

During the mixing operation, water is admitted into the spraying pipes of the respective hoppers in the manner as above described, and the particles of different materials are thus caused to adhere to form the pasty mixture desired.

By the movement of the slide valve 26, the 60 mixed material is permitted to be discharged therefrom into the chute 13 and delivered to a vehicle or any convenient receptacle provided for the purpose.

It is not desired to limit this invention to 65 the precise details of construction and ar-

rangement herein set forth, as it is obvious that various modifications may be made therein without departing from the essential features of the invention as defined in the appended claims.

Having described this invention, I claim:

1. In a concrete mixer, the combination with interposing mixing hoppers, each having an inlet and an outlet, of a surrounding casing operative to support said hoppers, a gate suspended by links within said casing dependent from each of said hoppers automatically actuated to control said outlet, and comprising opposed complementary jaws pivoted to said hoppers and co-operative with the walls thereof to govern its rocking movement, and yielding means tending to maintain said jaws in closed position to retain material in said hoppers, said material being effective to open said jaws in opposition to the closing means, by the accumulation of a predetermined weight of said material in said hopper.

2. In a concrete mixer, the combination with a plurality of interposing hoppers having tapering walls and each provided with an inlet and an outlet, of a surrounding casing operative to support said hoppers, means to control each of said outlets comprising complementary jaws pivoted to said hopper by relatively movable links dependent therefrom within said casing, and means tending to maintain said jaws closed, to retain material in said hopper, said jaws being automatically opened by the weight of material when a predetermined accumulation of said material is collected in said hopper, the weight of said material tending to frictionally engage said jaws with said hopper.

3. In a concrete mixer, the combination with a plurality of interposing hoppers having tapered walls, and each provided with an inlet and an outlet, of a cylindrical surrounding casing operative to support said hoppers, relatively movable links pivotally attached to said hoppers within said casing and forming pivots, conical gates comprising relatively movable complementary jaws arranged to rock on said pivots, forming closures for said outlets operative to retain material in said hoppers, and weights mounted on said jaws tending to maintain them in closed position, said gates being arranged to be automatically opened in opposition to said weights, by the pressure of a predetermined accumulation of material in said hoppers.

4. In a concrete mixer, the combination with a plurality of interposing hoppers, each having an inlet and an outlet, of a surrounding cylindrical casing operative to support said hoppers in spaced vertical relation, relatively movable links within said casing, gates for said hoppers forming receptacles with said hoppers to retain material when

- in position to close said outlets, and comprising substantially semiconical complementary jaws movably pivoted on said links to swing apart and to rock on said links, and means tending to maintain said gates closed, said material being effective to automatically open said gates when a predetermined accumulation is collected in said hoppers.
5. A concrete mixer comprising a plurality of interposing hoppers of substantially the form of a conoidal frustum, and each provided with an inlet and an outlet, a cylindrical surrounding casing operative to maintain said hoppers in spaced vertical relation, a gate for each of said outlets having hollow semi-conical complementary jaws, separately pivoted to links within said casing dependent from said hoppers and arranged to swing apart, weights carried by said jaws normally tending to maintain said gate closed to retain material in said hopper, and means including said material to open said gate in opposition to said weights by a predetermined accumulation of said material collected in said hopper, the rocking movement being governed by the walls of said hopper.
6. In a concrete mixer, the combination with a plurality of interposing hoppers, each provided with an inlet and an outlet, of a cylindrical surrounding casing operative to support said hoppers in spaced vertical relation, a gate for each of said outlets having inclined walls arranged to control said outlets, and comprising relatively movable complementary portions, each separately pivoted to links pivoted to said hopper within said casing, and weights carried by said complementary portions tending to maintain said gate closed to form a receptacle to retain said material in said hopper, said gate being arranged to be opened automatically by a predetermined accumulation of material collected in said hopper, and to be pressed into frictional engagement with the wall of said hopper by said accumulated material.
7. In a concrete mixing machine, the combination with a plurality of interposing hoppers, having downwardly curved converging walls, of conical gates operative to intermittently discharge the contents of each of said hoppers automatically, said gates being in frictional engagement with the sides of said hoppers, and downwardly curved flaring spreaders disposed subjacent to said hoppers.
8. In a concrete mixing machine, the combination with a plurality of interposing mixing hoppers, of a surrounding casing operative to support said hoppers, a curvedly flaring spreader interposed between said hoppers, relatively movable links comprising pivots dependent from said hoppers within said casing, and automatically actuated gates mounted to rock upon said pivots, arranged to be intermittently opened by the material accumulated in the respective hoppers to discharge said material upon the subjacent spreader.
9. In a concrete mixing machine, the combination with a plurality of mixing hoppers fixedly disposed one above the other, of an inlet hopper arranged to feed unmixed material to said mixing hoppers, means effected by the weight of the accumulated material to intermittently discharge said material from said mixing hoppers automatically, and means operatively connected to selectively admit water into said hoppers in predetermined sequence corresponding to the passage of the material through said hoppers, said means being operative to cut off the flow of water into one of said hoppers simultaneously with its admission into another of said hoppers.
10. A concrete mixing machine, comprising a plurality of interposing relatively stationary mixing hoppers, and an inlet hopper arranged to pour unmixed material into said mixing hoppers, automatic means arranged to control the discharge of material intermittently from the respective mixing hoppers, a spraying pipe local to each of the respective hoppers, separate valves operative to admit a flow of water into one of said spraying pipes and to contemporaneously shut off the flow of water in another of said pipes, in accordance with the movement of material from one hopper to another, and actuating means operative to simultaneously control both of said valves from one station.
11. A concrete mixing machine, comprising a plurality of mixing hoppers, and an inlet hopper arranged to feed unmixed material into said mixing hoppers, and having a spraying pipe arranged to direct jets of water into the respective hoppers, a supply pipe connected with said spraying pipes, valves disposed in said supply pipe operative to selectively supply water to said hoppers, each valve having a single inlet and a plurality of outlets, and means connected to contemporaneously control all of said valves from one station, one of said valves being operative to control the water supplied to the top hopper and to the other valve, said other valve being operative to supply water to the subjacent hoppers respectively, said valves being connected to direct water into each of said hoppers selectively, and to contemporaneously shut off the water from the other hoppers in sequence with the passage of the material through said hoppers.
12. In a concrete mixing machine, the combination with a plurality of interposing mixing hoppers having downwardly curved converging walls, of a feeding hopper operative to feed unmixed material to said mixing hoppers, conical gates opera-

tive to intermittently discharge the contents of each of said hoppers automatically, said gates being in frictional engagement with the sides of said hoppers, and upwardly curved flaring spreaders disposed subjacent to said hoppers.

13. In a concrete mixing machine, the combination with a plurality of interposing mixing hoppers having downwardly curved converging walls, of a feeding hopper operative to feed unmixed material to said mixing hoppers, a surrounding casing operative to support said hoppers, conical gates operative to intermittently discharge the contents of each of said hoppers automatically, said gates being in frictional engagement with the sides of said hoppers, and upwardly curved flaring spreaders disposed subjacent to said hoppers.

14. In a concrete mixing machine, the combination with a plurality of conoidal mixing hoppers, of a spreader interposed between said mixing hoppers, automatically actuated gates arranged to be intermittently

opened by the material accumulated in the respective hoppers to discharge said material upon the subjacent spreaders, and means suspending said gates and comprising relatively movable axes upon which said gates may rock.

15. In a concrete mixing machine, the combination with a plurality of conoidal mixing hoppers, of a spreader interposed between said mixing hoppers, automatically actuated gates arranged to be intermittently opened by the material accumulated in the respective hoppers to discharge said material upon the subjacent spreader, and links suspending said gates and comprising relatively movable pivots upon which said gates may rock.

In witness whereof, I have hereunto set my hand this 6th day of September, A. D. 1910.

DAVID B. HOOVER.
